UNITED STATES PATENT OFFICE.

CHARLES A. ANDERSON, OF CHICAGO, ILLINOIS, ASSIGNEE, BY DIRECT AND MESNE ASSIGNMENTS, TO G. E. SUNDSTROM, OF CHICAGO, ILLINOIS.

FLUID-PUMP.

14,789.

Specification of Reissued Letters Patent. Reissued Jan. 13, 1920.

Original No. 1,267,040, dated May 21, 1918, Serial No. 54,294, filed October 6, 1915. Application for reissue filed June 14, 1919. Serial No. 304,357.

To all whom it may concern:

Be it known that I, CHARLES A. ANDERSON, a citizen of the United States, and a resident of Chicago, in the county of Cook 5 and State of Illinois, have invented certain new and useful Improvements in Fluid-Pumps, of which the following is a specification.

My invention relates to fluid pumps, particularly to air pumps for inflating automobile tires.

My invention pertains to that class of pump adapted to be connected in driving relation with an automobile engine although 15 not limited thereto, and the general object of the invention is to produce a more simple and more efficient pump. One of the features of the invention is to provide improved construction and arrangement which dispenses with special valves, particularly 20 check valves, and to do all valving by means of the pump piston. Another feature is the improved simple connection between the piston and the crank shaft which will 25 cause combined reciprocatory and oscillatory movement of the piston in the cylinder in order that air passageways or channels in the piston may coöperate with inlet and outlet ports to efficiently control the in-flow 30 of air, the arrangement involving the reciprocation of the piston at right angles to the crank shaft. Another feature of my invention is the utilization of the crank case for compression and the utilization of such 35 compressed air in the cylinder together with the compression caused in the cylinder by the piston. Another feature involves arrangement for preventing the escape of lubricating oil from the cylinder into the air 40 delivery pipe. Another feature resides in permitting back-flow of compressed air into the cylinder to expand therein to effect cooling before the piston operation to compress air in the cylinder and discharge it therefrom, and another feature resides in the simplicity of the pump and the most efficient operation with a minimum number of parts.

Another important feature of the invention resides in improved mechanism for 45 readily connecting the pump in driving relation with the engine or another driving source.

The various features of the invention are

clearly illustrated on the accompanying drawings in which—

Figure 1 is a front elevational view of the pump with part of the cylinder broken away.

Fig. 2 is a side view from plane 2—2, Fig. 1,

Fig. 3 is a horizontal sectional view on plane 3—3, Fig. 1,

Fig. 4 is a side view from the left of Fig. 1, with the crank case cover removed, and

Fig. 5 is a complete vertical sectional view with the piston in its lower position.

An integral casting C provides the supporting base 10, the crank case 11, the crank shaft bearing sleeve 12, and the cylinder 13. 70 Journaled in the sleeve 12 is the crank shaft 14, whose inner end has the crank arm 15 terminating in the main bearing section 16, which together with the detachable bearing cap 17 forms a socket 18 for receiving the 75 ball 19 on the end of the horizontal limb a of the L-shaped connecting rod 20 whose vertical limb b at its upper end is pivoted to the wrist pin 22 which extends diametrically through the inverted cup-shaped piston 23. As shown, the wrist pin 22 is at 80 right angles to the crank shaft, and this arrangement together with the L-shaped connecting rod and its ball and socket connection with the crank arm causes combined 85 longitudinal reciprocation and axial oscillation of the piston when the crank shaft is rotated, the outer end of the crank shaft carrying a gear pinion 24 adapted for meshing engagement with a suitable driving gear 90 25 connected with the vehicle engine or other driving source.

The pump shown has the diametrically opposite air inlet and outlet ports 26 and 27 respectively, a suitable delivery pipe or hose 95 being in practice connected with the outlet port. On the air intake side the piston has the air inlet passageway or channel 28 cut in its face and communicating with the upper end of the cylinder. As the combined reciprocatory and oscillatory movement of the piston causes each point thereon to describe an ellipse the air passageway 28 is so curved and of such length that just after the piston begins its downward movement toward the crank case, the lower end

of the channel comes into communication with the intake port 26, and remains in communication with the port until the piston nears the lower extremity of its movement, whereupon such communication is interrupted; thus as the piston travels downwardly toward the crank case air will flow through the port 26 and channel 28 into the cylinder to be compressed during up-
stroke of the piston, the axial rotation of the piston when at the lower part of its stroke shifting the channel 28 away from and closing the intake port 26, which remains closed until just after the piston reaches the upper extremity of its movement and begins its downward movement.

At the air outlet side of the pump the piston has the short channel 29 cut in its face, its upper end being connected with the duct 30 which extends through the piston body to the top of the piston to communicate with the cylinder. This passageway 29 also extends elliptically in order that the channel will remain in communication throughout its length with the outlet port 27 as the piston travels. The relative arrangements of the passageways 28 and 29—30 is such that when the inlet passageway 28 approaches registration with the intake port 26 at the beginning of the down-stroke, the passageway 29 will leave the outlet port 27, and the passageway 29 will remain away from the outlet port until the piston has traveled clear down and upwardly a distance and effected some compression in the cylinder, the upper end of the channel then registering with the outlet port to permit the compressed air to escape through the channels 30 and 20 and the outlet port such escape continuing until the piston reaches the top of its stroke and terminating just before the air inlet channel 28 again comes into registration with the intake port 26. The relative positions of the piston channels and cylinder ports for the up-position of the piston are clearly shown in Figs. 1, 2 and 3, the piston being ready to rotate in the direction of the arrow and to move downwardly. Immediately upon rotating the channel 28 comes into registration with the air intake port and the outlet channel moves away from the outlet port and then during downward movement of the piston the channel 29 will be covered by the cylinder wall and the channel 28 will remain in communication with the intake port for the passage of air from atmosphere to the cylinder above the piston. In Fig. 5, the piston is shown in its lowest position, the upper end of the channel 28 having been carried just beyond the intake port to close it against air inlet, and then during upward movement of the piston both inlet and outlet channels will be closed by the cylinder walls until the piston has traveled upwardly a distance, and then

the channel 29 comes into registration with the outlet port 27 (dotted lines Fig. 3) whereupon the air compressed in the cylinder during the fore part of the upward stroke will escape through channels 30 and 29 and the outlet port. Just before the piston reaches the top the channel 29 will again leave the outlet port 27 and then when the piston starts to move downwardly the channel 28 will again come into registration with the intake port 26 to admit another charge of air from atmosphere into the cylinder.

I also provide for compressing air in the crank case and utilizing the compressed air. The crank case is closed to the exterior and therefore when the piston is traveling downwardly air will be compressed therein. In order to permit flow of this compressed air into the cylinder above the piston, either one or both of the piston channels may connect with the crank case at the lower end of the piston stroke, such connection being arranged to take place just after the closing of the inlet port 26. In Fig. 4 (dotted lines) and in Fig. 5 (full lines) the piston is shown in its lower position and it will be noted that the lower ends of channels 28 and 29 are open to the crank case. Compressed air can therefore flow from the crank case into the cylinder above the piston to equalize the pressure, and augment the volume of air in the cylinder, and then the compressed air in the cylinder will be further compressed when the piston is forced upwardly, this additional pressure from the crank case adding greatly to the capacity and efficiency of the pump. When the piston travels upwardly the air in the crank case will be expanded but atmospheric pressure is restored therein through the port 31 and the groove or passageway 32 cut in the piston surface, this groove being of a length to come into communication with the port 31 as the piston nears the upper extremity of its movement. The groove or channel 32 also extends in elliptical direction in order to keep communication with the port 31 as the piston turns, and the movement of the piston at the upper end of its stroke being practically a turning one, the channel will be disconnected from the port before the piston starts on its downward movement, and then the air in the crank case under atmospheric pressure will be compressed during down-stroke of the piston to be released into the cylinder above the piston through the channels 28 and 29 when the piston reaches its lower position.

The air channels on the piston are made of sufficient width to prevent clogging thereof by dust particles in the air and any such particles are quickly carried through the pump and prevented from accumulating therein. On account of the sliding valving

operation the pump is noiseless and there is no chance for the proper valving to fail.

In the lower part of the crank case there is preferably a charge of grease or oil of sufficient depth so that the crank arm and the end of the piston rod may splash therein to throw the oil about so as to lubricate the piston, and cylinder engaging surfaces and the bearings of the piston rod with the piston and crank. The grease or oil in the crank case also diminishes the air space and increases the compression therein. In the casting C I preferably leave the opening 33 at the crank case end and provide cover 34 therefor, this enabling inspection of the interior of the pump, and a smaller opening 35 can be provided in the cover for the charging of oil in the crank case and a plug 36 can be used to close the opening.

20 As the pump operates oil may tend to accumulate in the outlet channel 29 and flow through the port 27 into the delivery pipe and to the tire or other device to be inflated, will soon become greater than the pressure 25 in the cylinder when the channel 29 first comes into register with the outlet port 27 and there will therefore be a sudden and rapid flow of air into the cylinder and this in-rush of air will carry with it any oil in 30 the delivery pipe, port 27, or the piston outlet channels so that when the pressure in the cylinder does overcome that in the device to be inflated the air will flow through the passageways which have been cleaned of 35 oil or other accumulations. Furthermore, the sudden rush of air into the cylinder from the device to be inflated will by its expansion have cooling effect on the cylinder walls and piston. The exterior of the cylinder walls may also be corrugated or 40 flanged as shown to give extensive radiating and cooling surfaces.

In Figs. 1 and 5 the mechanism for controlling the coupling of the pump with a driving source is illustrated. Surrounding the crank shaft bearing sleeve 12 is the hub 37 from which extends the handle or lever 38. The outer end of the hub 37 extends beyond the sleeve 12 and encircles the inner hub 39 on the pinion 24 and this hub has the peripheral groove or run-way 40 for clutch balls 41 retained in pockets 42 in the hub 37, a sleeve 43 surrounding the hub 37 and engaging over the pockets 42 to confine 55 the balls therein and in the run-way 40. The bearing sleeve 12 has also the diagonally extending peripheral groove or run-way 44 for a ball 45 in the pocket 46 in hub 37, and a spring clip 47 secured by a screw 48 engaging over the pocket 46 to lock the ball 45 therein, and this screw preferably extends through the sleeve 43 and into the hub 37 to hold the sleeve in place on the hub. The pinion 24 is locked against rotation on the 60 crank shaft by the key 49 and is normally 65

out of the plane of its driving wheel 25. When it is desired to use the pump the lever 38 is swung laterally in the direction of the arrow (Fig. 2), and the ball 45 travels through the diagonal run-way 44, the hub 70 37 will be shifted outwardly along the crank shaft and the pinion 24 is shifted along the shaft with the hub and is brought into meshing engagement with the drive gear 25. It is evident that the hub 37 could be normally 75 out on the bearing sleeve 12 and the pinion 24 brought into driving relation with a gear by swinging the lever 38 to shift the hub inwardly. The ends of the diagonal run-way 44 are preferably deepened to form 80 pockets for more efficiently receiving the ball to yieldingly lock the hub 37 in its in and out positions on the bearing sleeve 12.

In order to prevent inward longitudinal movement of the crank shaft a ring 50 encircles the shaft in the peripheral groove 51 and is confined in the groove adjacent the outer end of the sleeve 12, by the under-cut end 52 of the pinion hub 39. In order to lubricate the crank shaft bearing surfaces 90 a channel 53 is cut through the shaft and is open to the crank case so that oil will be splashed thereinto and delivered to the bearing surfaces when the pump operates. By regulating the amount of oil or grease in 95 the crank case the compression space in the crank case can be made as desired. The greater the amount of oil or grease the less the compression space and the greater the compression.

By loosening screw 48 and withdrawing the plate 47 from the pocket 46 the ball 45 can be removed and then the hub 37 together with the pinion 24 can be removed. Withdrawal of the screw 48 will also release the sleeve 43 and this sleeve can then be readily rotated to bring the hole 54 therein successively into registration with the ball pockets 42 in order that the balls may be withdrawn whereupon the pinion can be 110 disconnected from the hub 37.

The bottom of the crank case may be integral with the casting C but preferably a removable bottom 55 is provided. With this removable bottom and the removable cover 115 34 it will be very easy to get at the piston rod and its crank and piston connections.

I do not of course desire to be limited to the exact constructions, arrangements and operations shown and described as modifications are no doubt possible which would still come within the scope of the invention.

I claim:

1. In a fluid pump, the combination of a cylinder, a piston, a crank shaft, connections 125 therebetween for effecting reciprocation and oscillation of the piston, inlet and outlet ports for said cylinder, air passageways in said piston for co-operating with the ports to regulate the flow of the fluid, a crank case 130

below said piston, fluid passageways serving to transfer compressed air from the crank case to the cylinder after preliminary compression in the crank case, a fluid vent in 5 said crank case, and a piston channel connecting with the vent to open the crank case to the outside on a predetermined outward movement of the piston.

2. In a fluid pump, the combination of a 10 cylinder, a crank shaft at right angles therewith, a piston within the cylinder, a wrist pin on the piston at right angles with the crank shaft when the piston is at the ends of its longitudinal reciprocation in the cylinder, a crank arm on said crank shaft, and an L-shaped connecting rod pivoted at one end on said wrist pin and pivoted at its other end to the crank arm, said connecting rod effecting combined longitudinal reciprocation 15 and rotary oscillation of said piston when the crank shaft is turned.

3. In a fluid pump, the combination of a 20 cylinder, a piston, a crank shaft; a connection between said piston and crank shaft adapted upon rotation of the crank shaft to effect combined longitudinal reciprocation and rotary oscillation of said piston, air inlet and outlet ports for said cylinder and air passageways cut in said piston for 25 operating with said ports to control the inflow and outflow of air, a closed crank case whereby air will be compressed in said case during in-stroke of the piston, means connecting said crank case with the cylinder at 30 the end of the in-stroke of the piston whereby air compressed in the crank case may flow into the cylinder, the air in said crank case being expanded during out-stroke of the piston, an atmosphere vent hole for said 35 crank case, said vent hole being closed during the greater part of the movement of said piston, and a channel cut in said piston for coöperating with said vent hole after a period of outward movement of said piston 40 to connect the crank case with atmosphere.

4. In a fluid pump, the combination of a 45 cylinder, a piston within said cylinder and crank shaft at right angles to said piston, said cylinder having an inlet at one side and an outlet at the other side and said piston having channels cut in its face to coöperate 50 with said inlet and outlet, a crank arm on said crank shaft, and a connection between said piston and crank arm adapted upon rotation of said crank shaft to effect combined reciprocation and oscillation of said piston during which movement said piston channels coöperate with the inlet and outlet to control the flow to and from said cylinder.

5. In a device of the class described, the 55 combination of a casing and piston forming a plurality of compression chambers, means operable to effect a relative composite reciprocal and rotary movement to the piston for 60 enlarging and diminishing said chambers,

and ports controlled by such composite movement to introduce and compress a charge in one chamber and transfer and further compress said charge in the other chamber and exhaust same from the latter chamber.

70

6. In a device of the class described, the 75 combination of a casing and piston forming a plurality of compression chambers therebetween, means for simultaneously imparting relative reciprocal and rotary movement to the piston, and ports and passageways in the casing and piston adapted to periodically intercommunicate by such reciprocal and rotary movement, so as to introduce a preliminary charge in one chamber and 80 thereafter supplement said charge by an auxiliary charge expressed from the other chamber and thereafter compress and expel the combined charge from the first mentioned chamber.

85

7. In a device of the class described, the 90 combination of a cylinder and crank case, a piston in the cylinder providing pressure chambers in the cylinder and crank case, a crank in the crank case connected with the 95 piston to simultaneously reciprocate and oscillate the piston, and thereby enlarge and diminish the pressure chambers in the cylinder and crank case, and ports in the wall of the cylinder controlled by the combined reciprocation and oscillation of the piston so as to admit preliminary charges in both the crank case and cylinder chambers, compress and transfer the charge in the crank case chamber to the cylinder chamber, and compress and discharge the combined charge 100 from the cylinder chamber.

95

8. In a device of the class described, the 105 combination of a casing comprising a crank case chamber and a cylinder chamber, a piston therebetween, means in the crank case connected with the piston for simultaneously reciprocating and oscillating the piston, a port controlled by the piston so as to temporarily open when the piston is projected outwardly in the cylinder and admit a charge to the crank case and close as the piston begins moving inwardly toward the crank case, so as to compress the charge in the crank case, an inlet port controlled by 110 the piston and adapted to open as the piston moves inwardly toward the crank case and admit a charge into the cylinder chamber and close thereafter to permit compression of the charge in the cylinder chamber, 115 a by-pass controlled by the piston so as to transfer the compressed charge in the crank case chamber to the cylinder chamber after the closing of the inlet port to the cylinder chamber and previous to the operation of 120 the piston for compressing the charge in the cylinder chamber, and an exhaust port controlled by the piston for exhausting the 125 combined charge from the cylinder chamber during compression.

130

9. In a device of the class described, the combination of a casing having a crank case chamber and a cylinder chamber, a piston therebetween, means in the crank case connected with the piston for imparting combined reciprocatory and oscillatory movement to the piston, an inlet to the crank case for admitting a charge so as to be compressed therein by the piston, an outlet from the cylinder chamber for exhausting a charge compressed therein, and a by-pass controlled by the combined reciprocatory and oscillatory movement of the piston to communicate the compressed charge from the crank case chamber to the cylinder chamber previous to compression in the cylinder chamber.
10. In a device of the class described, the combination of a casing having a crank case chamber and a cylinder chamber, a piston therebetween, means in the crank case connected with the piston for reciprocating and oscillating the piston, and inlet and outlet ports controlled by the reciprocation and oscillation of the piston to afford a comparatively long period of inlet communication with the cylinder chamber during the intake stroke, and to afford a comparatively short period of outlet communication from the cylinder chamber as the piston nears the end of the compression stroke.
11. In a device of the class described, the combination of a casing comprising a crank case chamber and a cylinder chamber, a piston therebetween, a rotatable crank in the crank case, an angular connecting rod having one arm connected with the piston and the other arm extending laterally from the axis of the piston, a ball on the outer end of the lateral arm and a ball socket on the crank engaging said ball for imparting combined oscillatory and reciprocal movement to the piston by rotation of the crank, and ports in the cylinder wall controlled by the combined oscillation and reciprocation of the piston for temporarily admitting air to the cylinder chamber and subsequently exhausting the air therefrom under pressure of the piston.

Chicago, Illinois, May 20th, 1919.

CHARLES A. ANDERSON.
